5 Claims. (Cl. 228—1)

The present invention relates to an elongated cylindrical tank having an open upper surface.

Tanks of the type under consideration are normally formed by assembling together a plurality of individual flat plate members such as by welding and supporting these members on a frame designed to resist the outward and downward loads imposed on the tank by its contents. Normally, such tanks are provided with bracing members across the upper surface of the tank to resist the tendency of the sides to move outward away from one another. Where such tanks are very long, it is normally impossible to construct the tank without some form of cross bracing across the upper surface.

Tanks of this sort are often used for electro plating or other chemical bath processes. The solutions normally contained within these tanks may attack the materials from which the tanks are constructed, such as steel and aluminum, and accordingly it is necessary to line the interior of these tanks to prevent the corrosion of the walls and the bottom. It will be appreciated that the protection of the interior of a tank wall appreciably adds to the over-all weight which the supporting structure is called upon to carry, as well as adding to the cost and complexity of manufacture.

Tank structures, in accordance with the teachings of the prior art, have normally been constructed at a location remote from the place where they are used, and it is frequently necessary to knock out the wall of a building to locate the finished tank in its working position.

The present invention overcomes the shortcomings of known tank structures by providing a tank which has only tensile stresses in its wall. Accordingly, there is no tendency for the walls of such a tank to deflect outwardly and there is no necessity to provide cross bracing over the top of the tank. Since only tensile stresses occur in the walls of the tank, the walls may be made of thin material, and where plating baths or other chemical solutions are contained in the tank, it becomes practicable to construct the walls of the tank from a non-corrosive metal. Further, since the walls of such a tank are subjected to tensile stresses only, these walls may be made very thin so that the wall structure of the tank may be carried within a plant as a rolled sheet of material and then assembled to the supporting structure to form the finished tank. It will be appreciated that a considerable saving in the cost of erecting a large tank will result where there is no necessity to remove the wall from a building in order to get the tank inside. The supporting structure for such a tank will similarly be much smaller and lighter than the supporting structure for a corresponding tank constructed in accordance with the teachings of the prior art.

The present invention provides a hollow frusto-cylindrical tank having a cross section orthogonal to its axis with a radius of curvature at a point on said cross section inversely proportional to the depth of said point below the surface of a liquid in said tank. Such a tank may readily be supported by a pair of support members extending longitudinally of the tank and fixed to the wall thereof at the free upper edges. There is no necessity to provide any cross bracing in such a tank, since the

forces exerted on the walls of such a tank are tensile only. Accordingly, it is only necessary to provide supports which may carry a load directed tangentially to the upper edge of the wall of the tank.

- 5 The invention further provides a hollow frusto-cylindrical tank having a pair of end walls, a continuous side and bottom structure, a pair of horizontal members adapted to support said side and bottom structure at the upper edges thereof, said side and bottom structure being formed of a single sheet of material and having a cross section orthogonal to the axis of the cylinder with a radius of curvature at any point on said cross section inversely proportional to the depth of the point below the surface of a liquid in said tank.
- 10 15 A tank structure in accordance with the present invention may have a cross section shape defined by the differential equation:

$$T = \frac{\gamma y \left[1 + \left(\frac{dy}{dx} \right)^2 \right]^{3/2}}{\frac{d^2y}{dx^2}}$$

where T is the tensile force in the wall per unit of tank length, where γ is the specific weight of the contained liquid, y is the depth below the free surface of the liquid to a point on the tank, and x is the horizontal distance to said point from the vertical axis of symmetry of the tank corresponding to the distance y below the surface of the liquid.

- 30 In drawings which illustrate an embodiment of the invention:

FIGURE 1 is a perspective view of a tank structure in accordance with the present invention; and

FIGURE 2 is a cross section of such a tank.

- 35 As shown in FIGURE 1, a tank 10 is provided with a continuous sheet wall surface 11 supported by the horizontal rails 12 and 13 fixed to the wall structure 11 by means (not shown). The rails 12 and 13 are shown supported on legs 14, 15 and 16. These legs are directed to be in line with a tangent of the curvature of the tank wall at the upper edge of the wall. The tank is provided with ends 17 and 18 to form the completed tank. As shown, end 17 is formed with a plurality of ribs 19 which serve to stiffen the ends of the tank.

- 40 45 As shown in FIGURE 2, the radius of curvature "R" of the tank varies throughout the depth "h" of the tank. The tank being symmetrical about the axis 20. In accordance with the invention, the radius of curvature R at a point 21 on the surface of the tank is inversely proportional to the distance "h" of the point 21 below the surface of the liquid contained in the tank. Expressed mathematically: $hR = K$, where K is a constant. Also, it will be appreciated that by varying the value of K and the positions of the support rails and the ends 17 and 18 of the tank, that tanks of different depths and widths can be formed.

- 50 55 Such a tank is characterized by the feature that the only forces existing in the wall of the tank are tensile forces and there are no forces directed other than in the plane of the walls.

- 60 65 Accordingly, the tank as described may readily be constructed of material which is much thinner than materials previously used. For example, a steel tank 3 feet in depth which might be used in electro plating need have a wall thickness of only 0.001 inch in order to support the plating solution. More usually, though, such a tank would be formed of 0.020 inch to give a safety factor.

- 70 Because of the use of very thin sheet to construct the tank, it becomes economically feasible to manufacture tanks from stainless steel, titanium or other expensive alloys. Such alloys have special properties which enable

them to resist the corrosive action of specific liquids. In conventional design, the weight of material required is so high that the cost may be prohibitive. In some cases, heavy steel tanks are lined or clad with a thin layer of expensive corrosion-resistant material. The new tank design eliminates the necessity for a heavy rigid supporting structure and is therefore less expensive.

The wall of the tank is so thin that it can frequently be fabricated flat. For example, a tank thirty-nine feet long and ten feet wide can be made by welding thirteen 3' x 20' strips together to make a flat sheet 39' x 20'.

Tank ends and the supporting structure can be built separately. The large sheet can be rolled up like paper and can be carried along with the tank ends and supporting structural members through a normal sized doorway into the building where it is to be used. A simple assembly job completes the tank. In this way, very large tanks may be produced at a manufacturer's plant and shipped to the consumer, whereas a conventional tanks would have to be constructed at the user's site.

In many cases, brick walls must be torn down in order to place large tanks in the user's premises. The present invention eliminates this requirement.

A most important aspect of the tank is that it may be made so that its sides are nearly vertical at the top. Such a tank needs no horizontal tie-bars to prevent the sides from bulging outwards. A tank of great length can be constructed using the same thickness of material which would be required for a short one. Such a tank is very useful in the electroplating industry where horizontal tie-bars would prevent long articles from being placed in and removed from the tank.

Another advantage is that the tank, having no corners, is very easily cleaned.

As previously mentioned, the differential equation describing the cross section of a tank constructed in accordance with the present invention may be written as follows:

$$T = \frac{\gamma y \left[1 + \left(\frac{dy}{dx} \right)^2 \right]^{3/2}}{\frac{d^2y}{dx^2}}$$

where T is the tensile force in the wall of the tank per unit of tank length; γ is the specified weight of the contained liquid, and y is the depth (previously referred to as "h") below the free surface of the liquid. The radius of curvature are $=T/\gamma y$ in the above equation.

From FIGURE 2 it is evident that the tank has boundaries and that the values thereof may be expressed as follows:

At $x=0$, $y=h$ (the maximum depth at tank centreline)

At $y=0$, $x=\frac{1}{2}$ tank top width

At $y=0$, $R=\infty$

At $x=0$, $dy/dx=0$

wherein R refers to the radius of curvature of the tank and is equal to $T/\gamma y$. The indication that R becomes infinite at $y=0$ provides for the tank shape becoming a straight line beginning at and above the x axis (a horizontal line coinciding with the illustrated liquid surface) as shown in FIGURE 2. Of course the last boundary value set forth above means the slope of the tank structure at its bottom is zero when $x=0$.

The equation above is the differential equation of the curve of the tank profile. This equation has not yet been solved to give a direct algebraic equation. A solution by successive approximation has been derived by means of which tanks can be conveniently designed.

For comparison, the algebraic and differential equa-

tions of the parabola and catenary are given as follows. It is readily seen that these are quite different from the above one.

5 Parabola:

Algebraic $x^2=2py$

$$\text{Differential } \frac{dy}{dx} = \frac{x}{p}$$

10 Catenary:

$$\text{Algebraic } y = \frac{a}{2} \left(\frac{x}{e^a} + \frac{-x}{e^a} \right)$$

$$\text{Differential } \frac{dy}{dx} = \frac{1}{2} \left(\frac{x}{e^a} - \frac{-x}{e^a} \right)$$

I claim:

1. An open top tank for holding a given liquid to a predetermined free surface level, comprising:

a pair of end walls,
a continuous side and bottom structure having a pair of longitudinal upper edges,
means secured to said edges for supporting said side and bottom structure only at the said upper edges thereof,
said side and bottom structure being formed of a sheet of material extending between said end walls and having orthogonal to the longitudinal axis of the tank a cross section with such a radius of curvature from the said liquid level downward that any point on said cross section is inversely proportional to the depth of the point below the said predetermined liquid surface level to cause a substantially constant tensile force in said structure per unit of tank length and to cause in conjunction with said supporting means substantially a zero transverse force in said structure at each of said upper edges.

2. A tank as in claim 1 wherein said supporting means includes a pair of horizontal members respectively extending lengthwise of said edges.

3. A tank as in claim 2 including in said supporting means a plurality of legs for supporting said horizontal members.

4. A tank as in claim 1 wherein the said cross section is defined in a vertical plane by the equation $hR=K$, wherein h is the aforesaid depth of a point on the cross section below the liquid level, R is the said radius of curvature at said point, and K is a constant including the said tensile force per unit of tank length.

5. A tank as in claim 4 wherein the said $K=T\gamma$, T being the said constant tensile force in the wall structure per unit of tank length, and γ being a constant representing the specific weight of the said given liquid, the horizontal force in said structure at $h=0$ being substantially zero.

UNITED STATES PATENT OFFICE
CERTIFICATE OF CORRECTION

Patent No. 3,199,710

August 10, 1965

Charles M. Hovey

It is hereby certified that error appears in the above numbered patent requiring correction and that the said Letters Patent should read as corrected below.

Column 4, lines 11 and 12, the equation should appear as shown below instead of as in the patent:

$$y = \frac{a}{2} \begin{pmatrix} x & -x \\ e^a & +e^a \end{pmatrix}$$

same column 4, lines 14 and 15, the equation should appear as shown below instead of as in the patent:

$$\frac{dy}{dx} = \frac{1}{2} \begin{pmatrix} x & -x \\ e^a & -e^a \end{pmatrix}$$

Signed and sealed this 3rd day of May 1966.
